CONTAINER FOR POLISHING WHEEL
COMPOSITION

Vernon J. Twyning, Grand Rapids, Mich., as-
signor to J. C. Miller Company, Grand Rapids,
Mich., a corporation of Michigan

Application November 22, 1937, Serial No. 175,757

2 Claims. (Cl. 51—263)

This invention relates to a composition container and the method of producing the same, the composition being generally a carrying body such as grease or the like, intermixed and carried in which is an abrasive, usually in finely divided form. This composition is applied to buffing and polishing wheels by bringing a stick of such composition against the surface of the wheel and applying it thereto while the wheel rotates.

In previous methods the composition which is put up in stick form was filled into a relatively short length of paper tubing, one end portion of the paper tubing having previously been provided with a partition across the same so that the tube when filled with the composition was filled from said partition to the other end of the tube. This required that in every case the tube which was to contain the composition should be cut to the specified length, have the partition placed across it a short distance from one end thereof, and then fill each tube individually with the composition.

It is an object and purpose of the present method to greatly facilitate the manufacture and production of the articles which consist of a tubular holder filled with the desired composition and which tubular holder at one end will have an extension of short length beyond the body of the composition and with a partition across and against which the composition contacts at one side, whereby the article can be handled without smearing the composition over the fingers of the operator and wherein the entire composition may be used up without waste. An understanding of my invention may be had from the following description, taken in connection with the accompanying drawing, in which,

Fig. 1 is a perspective view illustrating the application of the polishing or buffing composition to a polishing or buffing wheel, the composition holder and container of my invention being used.

Fig. 2 is a perspective view of an elongated paper tube which with the method herein is filled with the composition, and then cut transversely across into sections, each completely filled with the polishing or buffing composition.

Fig. 3 is an elevation of one of said sections.

Fig. 4 is an elevation, with one end portion in section, showing the tubular handle extension which is secured permanently to said end of the filled tube, and

Fig. 5 is a perspective view of said extension. Like reference characters refer to like parts in the different figures of the drawing.

With my method an elongated tube 1 usually of paper is filled for its entire length with the polishing or buffing composition indicated at 2. The tube thus filled is sawed or otherwise cut transversely at spaced apart intervals making a plurality of tubular sections 3 each completely filled from one end to the other with the composition.

An extension which serves as a handle by means of which the operator may handle the composition and apply it to the buffing wheel is provided, consisting of a short tubular member 4 within which a shallow cup having a bottom 5 and vertical sides 6 is inserted at one end and permanently secured as by gluing, both the member 4 and the cup preferably being of paper stock. The bottom of the cup 5 forms a partition across the tubular handle section 4. One end of the composition filled tube 3 is then inserted within the sides 6 of the cup and the parts glued or otherwise securely fastened together. This provides a composition stick in which the extension at 4 is recessed inwardly from its outer end to the bottom 5 of the cup, permitting easy handling of the stick and protecting the hands of the operator against the composition. And at the same time when the composition is to be applied to a buffing or polishing wheel such as 7 in Fig. 1 it may be applied until the whole composition has been used up.

The ability to fill an elongated tube, saw it across into sections of the desired length and, if wanted, of different lengths, and then attach the handle sections 4 thereto greatly decreases the cost of manufacture of articles of this type and character. The filling of a single elongated tube open from one end to the other is much more easily performed than the filling of several short tubes adjacent one end of each of which a cross partition has been secured. Moreover, the handle section 4 may be of greater strength than the walls or tube in which the composition is placed. The article produced is superior to that which has been produced by the old method.

The invention is defined in the appended claims and is to be considered comprehensive of all forms of structure coming within their scope.

I claim:

1. The combination with a tubular container filled with a dressing composition for buffing or polishing wheels, of a tubular handle member rigidly secured to said container, a transverse partition extending across said handle member spaced a substantial distance from each end

thereof, one end of said container being in contact with said partition.

2. The combination with a tubular container of paper material filled with a composition for buffing or polishing wheels, of a tubular handle member of shorter length and greater diameter than said container rigidly telescoped thereon

and secured thereto, a transverse partition extending across said handle member spaced a substantial distance from each end thereof, one end of said container being inserted into the handle member until stopped by said partition.

VERNON J. TWYNING.
